UNITED STATES PATENT OFFICE.

WALTER H. SCHMIDT, OF WINONA, MINNESOTA.

SANITARY CONE HOLDER.

Application filed March 25, 1921. Serial No. 455,622.

To all whom it may concern:

Be it known that I, WALTER H. SCHMIDT, residing at Winona, in the county of Winona and State of Minnesota, and a citizen of the 5 United States, have invented certain new and useful Improvements in Sanitary Cone Holders, of which the following is a specification.

The object, in general, of my invention is 10 to provide a sanitary protecting device for edible ice-cream cones, whereby a cone containing ice cream may be carried by the hand of a person and the ice cream protected against contamination by dirt and also 15 against melting as quickly as it would otherwise.

A further object is to provide a combined protecting device and holder for the cone; in other words, a device which may be used, 20 alternately, as a bonnet placed over the top of the filled cone to protect the ice-cream, and, in an inverted position, as a holder or support for the cone, when a person desires to use his hands in eating other things.

25 A further object is to provide a sanitary device, of the character indicated, which will be collapsible, that is, foldable into a flat position, so that the device may occupy a minimum of space, and whereby a maximum 30 number of the devices, in this collapsed position, may occupy a minimum space in shipment or storage.

A further object is to provide a device of this nature constructed in the form of a paper 35 receptacle, specifically, a box, which will be simple of construction and inexpensive to manufacture.

With these objects in view, the invention resides in the novel construction, combination, 40 and arrangement of parts of a paper receptacle or device, for the purpose described, as will be hereinafter fully described in the specification, summarized in the claim, and illustrated in the accompanying drawing.

45 The drawing discloses an exemplary construction capable of carrying out the underlying principles of the invention, and like reference - characters denote corresponding parts throughout the several views. Briefly described:

50 Figure 1 is a view in perspective of the device in operative position, as it appears when supporting a cone in an upright position, the apex of the cone being projected through an opening in the top of the device;

Figure 2 is a transverse vertical sectional view, on the line 2-2, Fig. 1, looking in the direction of the arrows;

Figure 3 is a view in perspective of the 60 device, the bottom and top flaps being shown open; and

Figure 4 is a central vertical sectional view through the device in an inverted position, showing the use thereof as a protecting bonnet, when the cone is being carried by a person, prior to eating thereof. 65

Referring, now, in detail, to the drawing:

1, 2, 3 and 4 designate the four rectangular, complementary walls of the rectangular 70 device, forming a box-like structure, preferably of paper, such as cardboard, of suitable thickness to present the requisite strength for the purpose intended. The meeting edges of the walls are creased, so as 75 to be flexible, whereby the box may be pressed into a flat position, for shipment or storage, in bulk.

Each of the walls 2 and 4 carries, at its bottom, a flap 5, adapted to be folded inward into the position shown in Fig. 2, so that said flaps are superposed.

The wall 3 carries, at its bottom, a flap 6, which is creased transversely toward its free end, as shown by the dotted line 7, so as 85 to form a tab 8 extending the width of said flap. The flap 6 is adapted to be folded against the lower flap 5, as shown in Fig. 2, and the tab 8 folded inward so as to lie against the inner surface of the wall 2, at 90 the bottom thereof, as shown in Figs. 1 and 2.

Each of the walls 2 and 4 also carries, at its top, a flap 9 provided with a curvilinear or arcuate cut-away portion 10, said 95 cut-away portions being complementary and oppositely disposed, so that, when said flaps are folded inward from the position shown in Fig. 3 to the position shown in Fig. 2, said cut-away portions will form a circular 100 aperture. The flaps 9, 9 are of such dimensions that, when folded toward each other, they overlap, as shown in Fig. 2, for purpose of strength.

The wall 3 also carries, at its top, a flap 105 11, having a circular opening 14, and being creased transversely toward its free end, along the dotted line 12, so as to form a tab 13 extending the width of said flap. The flap 11 is adapted to be folded down 110 upon the flaps 9, 9, as shown in Fig. 2, so as to lie thereupon, and the tab 13 is adapt-

ed to be projected inward, against the inner surface of the wall 1, toward the top thereof, as shown in Fig. 1. The circular opening 14, in this position of the parts, registers with the opening formed by the curved cut-away portions 10, 10; so that a cone 15, containing ice-cream, may be projected, apex downward, through said openings, the box thus constituting a support for the cone 10 to hold the same in an upright position, thus leaving the hands of the eater free for other purposes, as in eating other things.

My receptacle or device is admirably adapted for use in protecting the ice cream 15 in the cone from contamination by dirt or the like, and from melting as quickly as it otherwise would: As clearly shown in Fig. 4, wherein the box is inverted from the position shown in Fig. 1, so that the top of 20 the cone is within the box and the cone depends from the box through the opening 14 therein, in which position the cone may be carried by grasping the protruding end thereof, the box forming, as it were, a 25 protecting bonnet covering the top of the cone and the ice cream therein, so as to pro-

tect the latter from contamination while being carried, prior to eating, and protecting the ice-cream, also, from melting as quickly as it otherwise would.

Having thus fully described my invention, what I claim as new, and desire to secure by Letters Patent of the United States, is:

A collapsible holder for edible cones, comprising a paper box having oppositely disposed walls; a pair thereof carrying, at the top, flaps having complementary arcuate cut-away portions and having portions overlapping in the operative position of the 40 holder; and a third wall carrying, at its top, a flap resting upon said first two flaps in the operative position of the holder, and having a circular aperture registering with said cut-away portions, said circular-aper-tured flap being provided, at its otherwise free extremity, with a tab bearing against the inner surface of one of the walls of the holder in the operative position thereof.

In testimony whereof, I hereunto affix my signature.

WALTER H. SCHMIDT.
